UNITED STATES PATENT OFFICE

JOHN WILLIAM TERNAU, OF NEW LONDON, CONNECTICUT

FUEL-BURNER ATTACHMENT FOR FURNACES OR BOILERS

Application filed September 13, 1928. Serial No. 305,638.

This invention relates to improvements in fuel burners for use in furnaces to increase the combustion of the fuel and heating capacity of the furnace, and in raising steam in stationary and marine or other boilers, and it is the principal object of my invention to provide a furnace or boiler attachment producing a maximum of heat by a minimum consumption of fuel, such as oil under pressure forced through a burner and mixed with air under pressure produced by a fan driven by a motor, as for instance an electric motor.

Another object of my invention is the provision of a furnace attachment of the above type of comparatively simple construction, yet durable and efficient in its operation for the purpose in view, an attachment which will greatly reduce the cost of repairing and 20 of replacements for worn parts, as each part of the attachment is interchangeable and portable.

A further object of my invention is the provision of a furnace or boiler attachment 25 adapted to be readily attached to any size of furnaces or boilers of the present constructions without materially changing the furnace or boiler construction, and in which the air and fuel are imparted a whirling motion 30 ensuring a perfect combustion.

A still further object of my invention is the provision of a furnace or boiler attachment of this character which is equipped with a novel and improved burner plug and tip.

These and other objects and advantages of 35 my invention will become more fully known as the description thereof proceeds and will then be specifically defined in the appended claims.

In the accompanying drawings forming a material part of this disclosure:

Fig. 1 is a top plan view, partly in section of the boiler or furnace attachment, constructed according to my invention.

Fig. 2 is a top plan view of a front cover plate for the device, of Figure 1.

Fig. 3 is a section through the attachment on line 3—3 of Figure 1.

Fig. 4 is an inner front view of the burner plug.

Fig. 5 is a front elevation of a yoke bracket.

As illustrated, my improved and novel furnace attachment comprises a casting or casing 10 having an end flange 11 by means of which the device is adapted to be attached to a furnace or boiler front indicated at 12. At an appropriate place the casing 10 is provided with a lighting off hole 13 equipped with a movable cover 14.

A cover 15 having a handle 16 formed therewith is hingedly connected at one end, as at 17 to the casing 10, and has formed therewith intermediate its ends a substantially V-shaped ring adapted to engage a similarly shaped depression or groove in asbestos packing 18 embedded in the front wall 19 of the casing 10 of the furnace attachment.

A bracket 20 is attached at one end to an inner shoulder of the casing, extends into the same, and at its opposite end is secured to a lug or lugs 22.

A yoke 23 constituting a holder for an oil burner body 24, and parts associated therewith has at its inner apex a perforated boss 25 formed therewith equipped with inner thread allowing the passage of a screw bolt 26 which carries at its outer end a hand wheel 27, while its inner pointed end engages the burner body 24.

To the inner end of the yoke a two armed bracket 28 is secured by means of bolts and nuts 29 carrying suitable washers while the outer ends of the bracket arms are slotted, as at 30, to allow the securing of the yoke and burner therein to the bracket 20 by means of screws 31 carrying wing nuts 32 and encased in asbestos oil tight packings 33, so that the burner and its holder yoke can easily be taken apart and removed as a complete unit from the interior of casing or attachment 10.

The oil is supplied under pressure to the burner body by means of the oil supply pipe 34 in block 34' adapted to be centered therein by means of screws 34", and is fed through channel 35 in the burner body to the pipe 36 provided at its furnace end with a nozzle or tip 37.

This nozzle comprises a burner plug 38 screwed upon the end of pipe 36, which has

formed therewith three small openings 39 drilled on an angle from the face of the burner plug to the center hole through which the oil is forced through the center opening to the whirling space 40 of the tip 37.

It will be clear that the openings are made to size, and in accordance with the amount of fuel necessary to be consumed, and to produce the amount of heat required. This is also the case with the selection of the size of the whirling space 40, and the size of the hole in the center of the burner tip 37.

The angular face of the burner plug 38 is grooved, and the angular inner seat of the burner tip is also grooved, to ensure an oil tight joint when the tip is screwed onto the plug, thereby only allowing the fuel oil to pass through the angular grooves 39 cut in the face of the burner plug 38, and preventing leakage through the threaded section of plug and tip.

The object of cutting the grooves in the burner plug 39 at an angle and entering the whirling chamber is to give the fuel oil entering under pressure, a whirling motion and the oil being forced through a small hole in the center of the burner tip 37 produces a cone spray of oil film on entering the furnace or boiler while the air forced into the furnace by the fan device hereafter to be more fully described forms therewith a combustible mixture, and thereby produces combustion when ignited.

Deflector vanes or baffle plates 41 are arranged at the rear part of the attachment to ensure a suitable distribution of the air.

The air is forced into the attachment casing by a fan arrangement comprising a motor 42 attached to the casing door 15 my means 40 of a bracket 43 and having its shaft 44 equipped inside the door 15 with a fan 45.

The operation of my novel and improved furnace attachment will be clearly understood from the above description and simultaneous inspection of the drawing and it will be clear that the air forced by the fan into the furnace will be suitably deflected by vanes 41, while the fuel will enter the furnace in a whirl or spray imparted to it during its passage under pressure through the peculiarly shaped burner plug and tip so as to produce a combustible mixture developing a maximum of heating capacity with a minimum of fuel consumption.

It will be understood that I have described and shown as one example of the many possible ways of practically constructing my attachment its preferred form only, and that I may make such changes in its general arrangement and in the construction of its minor details as come within the scope of the appended claims without departure from the spirit of my invention and the principles involved.

Having thus described my invention, what

I claim as new, and desire to secure by Letters Patent is:

1. A furnace or boiler attachment of the class described adapted to be attached to a furnace or boiler, comprising a casing having a shoulder formed therein, an asbestos ring at the front end of said casing having a V-shaped groove formed therein, a door hinged to the front end of the attachment, an inner ring formed with said door equipped with a V-shaped inner face adapted to engage and fit into the groove of said ring, a bracket attached at one end to the shoulder of said attachment, and to lugs in the attachment at its opposite end, a burner, a means for supplying oil under pressure to said burner, a means for exchangeably securing said burner to said bracket, a means on said burner for imparting to the oil a whirling motion before its entrance into the furnace, a means for supplying air to said oil, and a means for imparting to said air a whirling motion before its mixture with the oil. 70

2. A furnace or boiler attachment of the class described adapted to be attached to a furnace or boiler, comprising a casing having a shoulder formed therein, an asbestos ring at the front end of said casing having a V-shaped groove formed therein, a door hinged to the front end of the attachment, an inner ring formed with said door equipped with a V-shaped inner face adapted to engage and fit into said ring, a bracket attached at one end to the shoulder of said attachment, and to lugs in the attachment at its opposite end, a burner, a means for supplying oil under pressure to said burner, a yoke, a perforated boss formed with the outer end of said yoke, a bolt screwed through said yoke, engaging said burner with its inner pointed end, a hand wheel at the outer end of said bolt, a two armed slotted bracket secured to the inner end of said yoke, and means engaging the slots of said bracket for exchangeably holding said burner in the attachment, a means on said burner for imparting to the oil a whirling motion before its entrance into the furnace, a means for supplying air to said oil, and a means for imparting to said air a whirling motion before its admixture with the oil. 95

3. A furnace or boiler attachment of the class described adapted to be attached to a furnace or boiler, comprising a casing having a shoulder formed therein, an asbestos ring at the front end of said casing having a V-shaped groove formed therein, a door hinged to the front end of the attachment, an inner ring formed with said door equipped with a V-shaped inner face adapted to engage and fit into said ring, a bracket attached at one end to the shoulder of said attachment, and to lugs in the attachment at its opposite end, a burner, a means for supplying oil under pressure to said burner, a yoke, 120

a perforated boss formed with the outer end of said yoke, a bolt screwed through said yoke engaging said burner with its inner pointed end, a hand wheel at the outer end 5 of said bolt, a two armed slotted bracket secured to the inner end of said yoke, and means engaging the slots of said bracket for exchangeably holding said burner in the attachment, a nozzle including a burner plug 10 having an angular, grooved face, connections between said nozzle and the burner body, a burner tip adapted to be screwed upon said plug, an inner angular grooved seat formed with said tip for imparting to the oil a whirling motion before its entrance into the furnace, a means for supplying air to the oil, and 15 a means for imparting to said air a whirling motion before its admixture with the oil.

4. A furnace or boiler attachment of the 20 class described adapted to be attached to a furnace or boiler, comprising a casing having a shoulder formed therein, an asbestos ring at the front end of said casing having a V-shaped groove formed therein, a door 25 hinged to the front end of the attachment, an inner ring formed with said door equipped with a V-shaped inner face adapted to engage and fit into said ring, a bracket attached at one end to the shoulder of said attachment, 30 and to lugs in the attachment, at its opposite end, a burner, a means for supplying oil under pressure to said burner, a yoke, a perforated boss formed with the outer end of said yoke, a bolt screwed through said yoke eng- 35 gaging said burner with its inner pointed end, a hand wheel at the outer end of said bolt, a two armed slotted bracket secured to the inner end of said yoke, and means engag- 40 ing the slots of said bracket for exchangeably holding said burner in the attachment, a nozzle including a burner plug having an angular grooved face, connections between said nozzle and the burner body, a burner tip adapted to be screwed upon said plug, an 45 inner angular grooved seat for imparting to the oil a whirling motion before its entrance into the furnace, a motor operated fan within the attachment for forcing air into the same, and deflector vanes or baffle plates arranged 50 at the rear part of the attachment to impart to said air a whirling motion before its admixture with the oil.

Signed at New London, in the county of New London and State of Connecticut, this 55 6th day of September, A. D. 1928.

JOHN WILLIAM TERNAU.
